MAGNETRON VACUUM TUBE

Paul Georges Chevigny, New York, N. Y., assignor
to Federal Telephone and Radio Corporation,
Newark, N. J., a corporation of Delaware

Application March 26, 1943, Serial No. 481,314

17 Claims. (Cl. 250—27.5)

1

This invention relates to improvements in vacuum tubes, and more particularly to magnetron oscillators adapted to provide high power at ultra-high frequencies.

An object of this invention is to provide a novel vacuum tube structure suitable for operation at extremely high frequencies, which at the same time is capable of handling large amounts of power.

Another object of this invention is directed to an improved magnetron oscillator having a high anode heat dissipation and being capable of handling large amounts of power.

A further object of this invention is directed to an improved magnetron oscillator in which the anode is readily capable of being cooled.

An additional object of this invention is to provide a magnetron oscillator in which a sealed hollow pipe serving both as an anode and as a tank circuit, projects from a sealed cathode support.

Other objects will become apparent from the following description taken in connection with the attached drawings showing several illustrative improvements of the invention, and wherein:

Fig. 1 is a longitudinal cross-sectional view of a preferred form of magnetron oscillator according to the present invention;

Fig. 2 is a transverse cross-sectional view taken along the line II—II of Fig. 1;

Fig. 3 is an enlarged cross-sectional view taken along the line III—III of Fig. 1;

Fig. 4 is an enlarged cross-sectional view of the coupling end of the magnetron illustrated in Fig. 1;

Fig. 5 is an enlarged cross-sectional view of a modified form of coupling end;

Fig. 6 is an end view of the coupling device illustrated in Fig. 5;

Fig. 7 is an enlarged cross-sectional view of a further modified form of coupling end for the magnetron;

Fig. 8 is an enlarged cross-sectional view of still another form of coupling end which may be used with the magnetron of Fig. 1;

Fig. 9 is a transverse cross-sectional view taken along the line IX—IX of Fig. 8; and

Fig. 10 is a partial enlarged cross-sectional view of a modified form of cathode structure which may be used in the magnetron illustrated in Fig. 1.

The vacuum tube according to the present invention is, as illustrated in Figs. 1 to 4 inclusive, of the magnetron type utilizing a hollow pipe 10, 10' both as an anode for the tube and as a hollow

2

resonant chamber. The two outwardly extending portions 10, 10' of the pipe are connected by a square portion 11 of reduced size, and in accordance with the preferred form of the present invention, the center bore of the pipe may be formed, for example, square, as is clearly shown in Figs. 2 and 3, but other shapes may be used, as desired. A cathode 12 which may be in the form of a hollow nickel cylinder coated with a suitable electron emissive material, such as a barium carbonate mixture, or a strontium carbonate mixture, is positioned within a transverse opening 13 extending through the reduced portion 11 of the pipe. About the ends of the opening 13 are attached, on opposite sides, a pair of copper cup-shaped members 14, 14' having a central opening disposed about and of the same size as the transverse opening 13. A second pair of smaller copper cup-shaped members 16, 16' are respectively positioned within the cup-shaped members 14, 14' and the peripheries of the two nested cup-shaped members are interconnected by means such as the annular glass seals 18 and 18' respectively.

One end of the cylindrical cathode 12 is attached to the bottom of one of the smaller cup-shaped members 16 as through the end shield 20. Cathode leads 22, 22' extend outwardly through a center bore in the opposite magnets 24, 24'.

The lead 22 is attached to the top side of the bottom of the cup-shaped member 16, while the lead 22' is attached to one end of a spiral heating element 26, the other end of which may be attached to the end shield 20 of the cathode cylinder 12. The lead 22' projects through a suitable opening in the opposite end shield 28 of the cylindrical cathode 12 and passes through and is supported by the bottom of the cup-shaped member 16'. It will thus be seen that the cathode supporting structure is formed of two individual units sealed to the narrowed portion 11 of the hollow pipe and so shaped as to receive the magnets 24, 24'.

The opening 13 in the narrow portion 11 of the hollow pipe permits an advantageous concentration of the magnetic field in the space between the cathode 12 and the surrounding portion 11 of the hollow pipe forming the anode. The bottoms of the cup-shaped members 16, 16' provide a screen which prevents radiation from passing between the surface of the cathode and the outer cup-shaped members 14, 14'.

The outward extension of the pipe as in portions 10, 10' projecting from the electrode section of the magnetron, permits a ready cooling

of the magnetron.

of such pipe as by the formation of cooling fins 30 on the surface of these ends, or by the use of any other cooling means, as will be apparent to those skilled in this art. One end 10 of the hollow pipe is covered with a cap 32 which may be brazed to the pipe itself to form an air-tight joint and serve as a reflector. The other end 10' may be formed with a coupling loop as is more clearly illustrated in Fig. 4. This end is covered by a cap 32' having an opening therethrough to which is connected a hollow sleeve 34 projecting outwardly of the cap. The outer end of the sleeve 34 is sealed with a glass bead 36 which, at the same time, serves to support a loop 38 projecting inwardly through the sleeve 34 to within the hollow pipe end 10'. The loop 38 serves to couple the magnetron oscillator with another device, as exemplified, by way of example, by the surrounding pipe 40.

Another arrangement to provide coupling from the magnetron is illustrated in Figs. 5 and 6. In this case the hollow end 210' of the magnetron oscillator is provided with the cap 232'. Between the cap 232' and the pipe end 210' is positioned a copper or other metal disk 270 having a narrow slot 272 therethrough. The outside of the pipe is sealed by means of a mica disk 274 placed over the outer side of the copper disk 270 and sealed beneath the cap 232'. For sealing purposes, a suitable fusing enamel may be placed about the edge of the mica disk.

A slightly different form of coupling is illustrated in Fig. 7. In this case the hollow pipe end 310' is covered by an end cap 332', and between the cap and pipe end is positioned a copper disk 370 having a narrow slot 372. A mica disk 374 is placed over the opposite side of the copper disk 370 while a second copper disk 380 having a narrow slot 382, aligned with the slot 372, is positioned about the outside of the mica disk and pressed against the same through the action of the cap 332'. By this arrangement the mica disk is protected, as compared with the structure illustrated in Figs. 5 and 6.

A still further coupling arrangement is illustrated in Figs. 8 and 9. In this case the hollow pipe end 410' is formed with a reduced section 492 about which is connected an end cap 494 provided with a narrow slot 493. The cap 494 may be attached to the reduced section 492 by any suitable means such as screws 498. A copper sleeve 520 is sealed at one end about the larger portion of the pipe end 410', the other end of this copper sleeve spreads outwardly for sealing connection with the periphery of a glass cup 502 which surrounds and encloses the reduced portion 492 of the hollow pipe and its attached slotted cap 494. The larger portion of the hollow pipe 410' may also be provided with a radial flange 496 to which may be threaded a hollow pipe 440 of the device to which coupling is desired.

The specific type of cathode illustrated in Fig. 1 may be replaced by other types of known cathodes. For example, in Fig. 10, I have illustrated an adaptation of a cathode structure such as illustrated in my copending application, S. N. 474,968, filed, February 6, 1943, in which the electron emitting surface is formed by a helical coil 112 wound on spaced supports 150 and heated by bombardment from a spiral filament 126. In this case the supporting rods 150 are mounted from the underside of the bottom of the cup-shaped member 16 through an inverted cup 152, while the filament 126 is mounted on a central supporting rod 154 which serves as an inner 70

filament structure. The other end of the filament 126 is connected to a hollow tubular conductor 156 which projects outwardly through the bottom of the cup-shaped member 16' and through a suitable bore in the magnet 24'. The outer end of the tubular conductor 156 is sealed as by a glass bead 157 which also serves as an outer support for the rod 154. The rod 154 may be held within the tubular conductor 156 as by spaced insulators 158 and 160.

While I have described above the principles of my invention in connection with certain specific structure and particular modification thereof, it is to be clearly understood that this description is made only by way of example and not as a limitation on the scope of my invention as set forth in the objects and the accompanying claims.

I claim:

1. An electron discharge device including, an anode comprising a hollow metal pipe having a transverse opening therethrough intermediate its ends, means sealing one end of said pipe, a cathode extending through the transverse opening in said pipe and positioned substantially centrally within the hollow pipe, means attached to the opposite sides of said pipe about said transverse opening sealing said opening and supporting said cathode, magnets positioned on opposite sides of said hollow pipe and extending outwardly from said transverse opening, and sealing means attached to the other end of said hollow pipe.

2. The combination according to claim 1, in which said last sealing means includes a cap on the other end of said hollow pipe, a hollow sleeve extending through and projecting outwardly from said cap, a coupling loop extending through said sleeve, having one end positioned within the hollow pipe and the other end projecting beyond the outer end of said sleeve, and a seal in the outer end of said sleeve through which said loop passes.

3. The combination according to claim 1, in which said last sealing means includes a cap having a central opening on the other end of said hollow pipe, a metal disk provided with a narrow coupling slot intermediate said cap and the said other end of said pipe, and a mica disk sealed to said cap, covering said slot and the outside of said metal disk.

4. The combination according to claim 1, in which said last sealing means includes a cap having a central opening on the other end of said hollow pipe, a metal disk provided with a narrow coupling slot intermediate said cap and the said other end of said pipe, a mica disk sealed to said cap, covering said slot and the outside of said metal disk, and a second metal disk covering said mica disk, and provided with a narrow slot aligned with the slot in the first metal disk.

5. The combination according to claim 1, in combination with a metal cap having a narrow slot attached on the other end of said hollow pipe, and in which said last sealing means comprises insulating means sealed to the said other end of the pipe and surrounding said slotted metal cap.

6. The combination according to claim 1, in combination with a metal cap having a narrow slot attached on the other end of said hollow pipe, and in which said last sealing means comprises a glass cup surrounding said other pipe end and said slotted cap, and a metal sleeve sealed at one end about the said other end of the

hollow pipe, and at its other end sealed to the periphery of said glass cup.

7. An electron discharge device including, a hollow metal pipe having a transverse opening therethrough, a pair of metallic cup-shaped members each having a hole in its bottom, respectively positioned on opposite sides of said pipe about the opening therethrough, the holes in the bottoms of the cup-shaped members being aligned with the opening through said pipe, a pair of second smaller metal cup-shaped members respectively nestled within the first cup-shaped members with the bottoms of the first cup-shaped members spaced from the bottoms of the second cup-shaped members, sealing means interconnecting the peripheries of each pair of nestled cup-shaped members, a cathode supported between the opposed bottoms of the smaller cup-shaped members and positioned within the hollow metal pipe, a magnet positioned within each smaller cup-shaped member, means sealing one end of said hollow pipe and coupling means connected to the other end of said hollow pipe.

8. The combination according to claim 7, in which the inside of said hollow pipe is formed as a substantially square bore and the outer surface of said pipe is formed substantially square adjacent the said openings, in combination with radially extending fins on both ends of said pipe.

9. The combination according to claim 7, in which said coupling means includes a cap on the other end of said hollow pipe, a hollow sleeve extending through and projecting outwardly from said cap, a loop extending through said sleeve, having one end positioned within the hollow pipe and the other end projecting beyond the outer end of said sleeve, and sealing means in the outer end of said sleeve through which said loop passes.

10. The combination according to claim 7, in which said coupling means includes a cap having a central opening on the other end of said hollow pipe, a metal disk provided with a narrow slot intermediate said cap and the said other end of said pipe, and a mica disk sealed to said cap, covering said slot and the outside of said metal disk.

11. The combination according to claim 7, in which said coupling means includes a cap having a central opening on the other end of said hollow pipe, a metal disk provided with a narrow slot intermediate said cap and the said other end of said pipe, a mica disk sealed to said cap, covering said slot and the outside of said metal disk, and a second metal disk covering said mica disk, and provided with a narrow slot aligned with the slot in the first metal disk.

12. The combination according to claim 7, in which said coupling means includes a metal cap having a narrow slot attached on the other end of said hollow pipe and insulating means sealed to the said other end of the pipe and surrounding said slotted metal cap.

13. The combination according to claim 7, in which said coupling means includes a metal cap having a narrow slot attached on the other end of said hollow pipe, a glass cup surrounding said other pipe end and said slotted cap, and a metal sleeve secured at one end about the said other end of the hollow pipe, and at its other end sealed to the periphery of said glass cup.

14. The combination according to claim 7, in

which said cathode comprises means forming a hollow cylindrical electron-emitting surface and a heating coil within said cylindrical surface, in combination with means attaching said surface-forming means to the underside of the bottom of one of said smaller cup-shaped members, and means connected to said heating coil attached to the bottom of the other of said smaller cup-shaped members.

10 15. The combination according to claim 7, in which said cathode comprises means forming a hollow cylindrical electron-emitting surface and a heating coil within said cylindrical surface, in combination with means attaching said surface-forming means to the underside of the bottom of one of said smaller cup-shaped members, means attaching one end of said heating coil to said last means, and means connected to the other end of said heating coil and attached to the bottom of the other of said smaller cup-shaped members.

which said cathode comprises means forming a hollow cylindrical electron-emitting surface and a heating coil within said cylindrical surface, in combination with means attaching said surface-forming means to the underside of the bottom of one of said smaller cup-shaped members, means attaching one end of said heating coil to said last means, and means connected to the other end of said heating coil and attached to the bottom of the other of the smaller cup-shaped members.

10 15. The combination according to claim 7, in which said cathode comprises means forming a hollow cylindrical electron-emitting surface and a heating coil within said cylindrical surface, in combination with means attaching said surface-forming means to the underside of the bottom of one of said smaller cup-shaped members, means attaching one end of said heating coil to said last means, and means connected to the other end of said heating coil and attached to the bottom of the other of the smaller cup-shaped members.
